UNITED STATES PATENT OFFICE.

ROBERT SMITH, OF GRAND RAPIDS, MICHIGAN, ASSIGNOR, BY DIRECT AND MESNE ASSIGNMENTS, OF ONE-HALF TO HERBERT B. GILLETTE, OF GRAND RAPIDS, MICHIGAN, AND ONE-HALF TO THE MICHIGAN TRUST COMPANY, RECEIVER OF E. G. PETERS MANUFACTURING COMPANY.

METHOD OR PROCESS FOR FINISHING BEARING-ROLLERS.

1,122,433.

Specification of Letters Patent. Patented Dec. 29, 1914.

Application filed January 25, 1910. Serial No. 540,049.

To all whom it may concern:

Be it known that I, ROBERT SMITH, a citizen of the United States, residing at Grand Rapids, Michigan, have invented certain new and useful Improvements in Methods or Processes for Finishing Bearing-Rollers, of which the following is a specification.

This invention relates to improvements in methods or processes for finishing bearing rollers.

The main object of this invention is to provide an improved method or process for finishing bearing rollers which enables 15 the rapid and economical production of substantially perfect rollers.

Further objects relative to details will definitely appear from the detailed description to follow, in which the details of my 20 improved method or process are set forth.

In carrying out my improved method or process I preferably employ the apparatus or machine illustrated in the accompanying drawing, in which:

25 Figure 1 is a plan view. Fig. 2 is a vertical section taken on a line corresponding to line 2—2 of Fig. 1. Fig. 3 is a detail of the member 12. Fig. 4 is a detail of the member 13. Fig. 5 is a side elevation of one 30 of the rollers which the structure illustrated is especially designed to finish.

In carrying out my improved process, the rollers are first formed by a screw machine or the like. They are then placed in a machine 35 having coacting finishing members adapted to receive them along with master rollers of high-speed steel or the like, and brought to substantially uniform size. At least one of said finishing members is revoluble, or 40 movable, so that the rollers are revolved under pressure, the feeding finishing member being preferably adapted to remove surplus metal. The rollers are then taken from the machine, case hardened and replaced in 45 the machine, a feeding member having a finishing surface being substituted for the cutting member. This removes any irregularity which may have been produced by the case hardening operation and reduces the 50 rollers to a uniform size and shape and polishes the same.

I will now describe the machine which I preferably use for this purpose, the same being made the subject matter of my application for Letters Patent, Serial No. 55 540,050, filed Jan. 25, 1910, which has matured into Patent No. 1,098,336, granted May 26, 1914.

In the accompanying drawing, similar reference characters refer to similar parts 60 throughout the several views; and the sectional views are taken looking in the direction of the little arrows at the ends of the section lines.

Referring to the drawing, the support or 65 base 1 is provided with projecting ears 2, adapted to receive the securing bolts 3 by means of which the support is secured upon a table, or other suitable bed.

The support 1 is provided with an annular seat 4. In this seat I arrange a finishing member 5, preferably a ring having an annular finishing surface 6 adapted to act on one end of the rollers to be finished, as at 8. These rollers illustrated are conical 70 and of uniform taper from end to end, and provided with conical small ends 8 and convex large ends 9, (see Fig. 5). On this member 5 I arrange the finishing member 10 which is preferably a ring having an inclined annular finishing surface 11 thereon, adapted to act on the sides of the rollers 7. I also provide finishing members 12 and 13 75 for the large ends of the rollers. These finishing members are provided with annular finishing surfaces 14 and 15, respectively, the surface 14 of the member shown being toothed, while that of the member 13 is a smooth or polishing surface, as 15.

The finishing surfaces 14 and 15 of the 90 members 12 and 13 illustrated are curved in cross section to form the convex ends of the rollers. The finishing surfaces 6 and 11 of the members 5 and 10 illustrated are smooth surfaces. These finishing members 95 are formed of steel, preferably of tool steel. A coacting rotatable finishing member 16 is provided, having a conical finishing surface 17, which acts on the sides of the rollers to be finished. A feed member 18 is provided 100 for the finishing members 12 and 13, the feed member being provided with a seat 19.

adapted to receive either of the members 12 and 13. The member 18 is threaded into the support 1 so that it can be fed downwardly to force the rollers to the finishing members 5, 10 and 16. The member 18 is preferably adjusted by providing the same with a lever 20 having a hole 21 therein adapted to be engaged over the pin 22 on the support 1.

10 The rotatable member 16 is provided with a driving shaft 23, the driving means not being here illustrated. The master rollers are shown at 24. These master rollers are of the size of the finished rollers or slightly 15 smaller. These master rollers are preferably made of high speed steel. In carrying out my improved method, the rollers are just turned out with a screw machine or the like. They are then placed in the machine described, and the cutting member 12 inserted in the feed member 19. This is gradually fed down, and as the metal is forced up on the rollers by the finishing members acting on the sides thereof, it is 20 cut or ground off by the member 12. The finishing member 13 is then substituted for the cutting member and the rollers replaced in the machine along with the master rollers, and the machine operated to bring the 25 rollers to uniform size. The rollers are then removed from the machine and case hardened. They are then replaced in the machine along with the master rollers, the polishing or finishing member 13 being used, 30 the machine again operated until the rollers are brought to a nice polish or finish and any irregularity or roughness produced by the case hardening removed. By this 35 process I am enabled to very rapidly and 40 economically produce perfect rollers which have a very fine finish throughout.

The machine illustrated is adapted for the finishing of tapered rollers having conical small ends and convex large ends, as shown 45 in the drawing.

Having thus described my invention, what I claim as new and desire to secure by Letters Patent is:

1. The method of finishing conical bearing rollers, consisting of associating and arranging a plurality of such rough cut rollers in substantially their coacting relation with master rollers of correct dimensions interspersed therebetween, acting on the same by 50 rotating finishing members conformed thereto in contact with the sides thereof and thereby revolving said rolls, applying a cutting tool to the ends of said rollers when thus revolving, thereafter applying a bur- 55 nishing tool to the ends of said rolls with said master roller present, hardening said rolls by a suitable process, and again associating and arranging the said hardened rolls with master rolls and subjecting them 60 to a burnishing contact with suitable rotating 65

finishing tools on their sides and to a burnishing tool on their ends, while revolving, to burnish the same, as specified.

2. The method of finishing conical bearing rollers, consisting of associating and arranging a plurality of such rough cut rollers in substantially their coacting relation, acting on the same by rotating finishing members conformed thereto in contact with the sides thereof and thereby revolving said 70 rolls, applying a cutting tool to the ends of said rollers when thus revolving, thereafter applying a burnishing tool to the ends of said rolls with said master rollers present, hardening said rolls by a suitable process, 75 and again associating and arranging the said hardened rolls with master rolls and subjecting them to a burnishing contact with suitable rotating finishing tools on their sides and to a burnishing tool on their ends, 80 85 while revolving, to finish the same, as specified.

3. The method of finishing conical bearing rollers, consisting of associating and arranging a plurality of such rough cut rollers in substantially their coacting relation, acting on the same by rotating finishing members conformed thereto in contact with the sides thereof and thereby revolving said 90 rolls, applying a cutting tool to the ends of said rollers when thus revolving, hardening said rolls by a suitable process, and again associating and arranging the said hardened rolls with master rolls, and subjecting them to a burnishing contact with suitable rotating finishing tools on their sides and to a burnishing tool on their ends, while revolving, 95 to finish the same, as specified.

4. The method of finishing conical bearing rollers, consisting of associating and arranging a plurality of such rough cut rollers in substantially their coacting relation with master rollers of correct dimensions interspersed therebetween, acting on the same by rotating finishing members conformed thereto in contact with the sides thereof and thereby revolving said rolls, applying a cutting tool to the ends of said 100 rollers when thus revolving, and thereafter applying a burnishing tool to the ends of 105 said rolls with said master rollers present.

5. The method of finishing conical bearing rollers, consisting of associating and arranging a plurality of such rough cut rollers in substantially their coacting relation with master rollers of correct dimensions interspersed therebetween, acting on the same by rotating finishing members conformed thereto in contact with the sides thereof and thereby revolving said rolls, 110 thereafter applying a burnishing tool to the end of said rolls with said master rollers present, hardening said rolls by a suitable process, and again associating and arranging the said hardened rolls with master 115 rollers present.

rolls, and subjecting them to a burnishing contact with suitable rotating finishing tools on their sides and to a burnishing tool on their ends, while revolving, to finish the 5 same, as specified.

6. The method of finishing conical bearing rollers, consisting of associating and arranging a plurality of such rough cut rollers in substantially their coacting relation, 10 acting on the same by rotating finishing members conformed thereto in contact with the sides thereof and thereby revolving said rolls, thereafter applying a burnishing tool to the ends of said rolls with said master 15 rollers present; hardening said rolls by a suitable process, and again associating and arranging the said hardened rolls with master rolls and subjecting them to a burnishing contact with suitable rotating finishing tools on their sides and to a burnishing tool on their ends, while revolving, to finish the 20 same, as specified.

7. The method of finishing conical bearing rollers, consisting of associating and arranging a plurality of such rough cut rollers in substantially their coacting relation, 25 acting on the same by rotating finishing mem-

bers conformed thereto in contact with the sides thereof and thereby revolving said rolls, hardening said rolls by a suitable 30 process, and again associating and arranging the said hardened rolls with master rolls and subjecting them to a burnishing contact with suitable rotating finishing tools on their sides and to a burnishing tool on 35 their ends, while revolving, to finish the same, as specified.

8. The method of finishing conical bearing rollers, consisting of associating and arranging a plurality of such rough cut rollers 40 in substantially their coacting relation, supporting said rough cut rollers in correct relation to rotating finishing members, and acting on said rollers by said rotating finishing members conformed thereto and in contact with the sides thereof and revolving said rollers, substantially as specified.

In witness whereof, I have hereunto set my hand and seal in the presence of two witnesses.
